BOX BAND STRETCHING AND SEALING
TOOL

Clarence O. Carlson, East Cleveland, Ohio, assignor to The American Steel and Wire Company of New Jersey, a corporation of New Jersey

Application November 22, 1934, Serial No. 754,327

2 Claims. (Cl. 81—9.1)

This invention relates to fastening tools in general, and is particularly concerned with fastening tools for the ends of package strapping, one of the objects being to produce firmly strapped packages. Since a tool may include a mechanism capable of interfastening the ends of strapping with varying degrees of security dependent on the extent of its operation, another object is to assure reasonable fastening security. Other objects may be inferred.

A specific example of a tool embodying the features of the invention and adapted to hand strip or band strapping, is illustrated by the accompanying drawings, in which:

Figure 1 is a side view.

Figure 2 is a top view.

Figure 3 is a longitudinal section from the line III—III in Figure 2.

Figure 4 is a longitudinal section from the line IV—IV in Figure 1.

Figure 5 is a longitudinal section from the line V—V in Figure 1.

Figure 6 shows details on the side opposite to that shown by Figure 1.

Figure 7 is a cross-section from the line VII—VII in Figure 4.

Figure 8 shows a fastening element adapted for use with the tool.

Figure 9 is a cross-section of the fastening resulting from the use of this element.

Referring to these drawings:

The tool includes a base 2 to which a side frame 3 is pivoted by way of a pin 11 which is subsequently described. A pinch block 4 is screwed in this base 2 and is held in any desired adjustment by means of a spring 5 which is insertable in any one of several radial slots 6 cut in the bottom face of this block 4. The surface of this block is checkered so as to grip the lower of two overlapping ends of a box strapping and hold it securely. Two pinch wheels 7 are disposed adjacent the pinch block 4, the faces of these wheels having teeth which engage the upper of the overlapping ends of the box strapping, the revolving of these wheels causing the end of the strapping to be pulled through the tool and thus tensioning the band.

Placed between the wheels 7 and fastened thereto by pins 8 is a ratchet wheel 9. On each side of the wheels 7 is a link 10 which rotates about a pin 11 on a sleeve 12. This sleeve also supports the wheels 7 and 9. A link 13 is connected to the links 10 by means of a pin 14 on which is also fastened a pawl 15. The link 13 is connected to a lever 16 by a pin 17. The lever 16 is pivoted to the base 2 by a pin 18. To insure the pawl 15 engaging the teeth of the ratchet wheel 9, a spring 19 is arranged to bear against the back of the pawl 15, this spring being supported by a pin 20. A stationary pawl 21 is

supported by a pin 22 and is held in engagement with the ratchet wheel 9 by a spring 23. Downward movement of the lever 16 causes the pawl 15 and the pinch wheels 7 to rotate about the pin 11, thereby tensioning the box strapping. The pinch wheels 7 must be so supported that they can be lowered to engage the box strapping while tensioning the same, and also so they can be raised for removing the tool from the band after fastening is completed. To accomplish this, that portion of the pin 11 on which the pinch wheels 7 rotate is set off-center, so that by rotating the pin 11 the wheels 7 may be raised or lowered.

The mechanism which makes the fastening includes two co-acting jaws 24 which are pivotally supported in the side frame 3 by pins 25. The lower parts of the jaws 24 hold dies 26, the latter having shearing surfaces 27 which are adapted to shear the edges of the box strapping. The dies 26 are held in place by means of screws 28. A block 29 is also held rigidly in place in the side frame 3 by screws 30. This block 29 determines the position of the box strapping and the sleeve 33. A plurality of slots are cut in the longitudinal edges of the block 29 to allow projections 31 of the dies 26 to enter slots 32 of the sleeve 33, thus allowing the shearing surfaces 27 of the dies 26 to engage the edges 34 of the box strapping 35 and shear this box strapping along the edges 36 of the slots 32. A plurality of recesses 37 are cut on the face 38 of the jaw 24 to receive the part of the box strapping 35 which has been bent down to a point below the surface 38.

The upper ends of the jaws 24 are connected to links 39 and 40 by pins 41. These links are fastened together at their other ends by a pin 42 which is also fastened to a crosshead 43. This crosshead is fastened to a link 44 by a pin 45. The upper end of the link 44 is fastened to an operating lever 46 by a pin 47. This operating lever 46 is supported in the side frame 3 by a pin 48. The upper portion of the side frame 3 is formed into a U-shaped handle 49 in which the lever 46 is held when in its upper position by a spring 50, the latter engaging a depressed portion 51 of the lever 46. This lever is shown in down position at the completion of a fastening operation. The jaws 24 are moved to an open position by moving the lever 46 upward.

The tool is provided with a locking mechanism, by the operation of which the operating lever 46 must be brought to a determinable operating position before it can be returned to its upper position. This insures a uniform depth of shear along the edges 36 of the band 35, thus making all fastenings of uniform security, the tool being obviously capable of interfastening the ends of the strapping with varying degrees of security dependent on the extent of its operation, due to

the fact that the further the lever 46 is thrown the greater will be the depth of shear and the more secure will be the interfastening effect. The locking mechanism includes a lever 52 which is pivoted 5 to the side frame 3 by a pin 53. A locking pin 54 is fastened to the lever 52 by a pin 55. The opposite end of the pin 54 is slidably held in a hole in the side frame 3. A latch 56 is pivotally supported at the upper end of the lever 52 by a pin 10 57. This latch 56 is held yieldingly against a surface 58 by a spring 59. An adjustable stop pin 60 is provided to control the lower limit of travel of the lever 46. This pin 60 has a hole longitudinally through its center in which a slideable 15 pin 61 rides. This pin 61 works against a screw 63 fixed to the lever 52. When the lever 46 approaches its extreme lower position a face 62 of the lever engages an end of pin 61 and causes the opposite end of this pin to engage the lever 52 so 20 as to, in turn, cause the latch 56 to latch on the surface 58. With the latch 56 in this position the crosshead 43 can move up past the end of the locking pin 54. When the lever 46 approaches its extreme upper position, the surface 65 of this 25 lever engages the latch 56 which is thus released from engagement with the surface 58, a spring 66 causing the locking pin 54 to rest against the crosshead 43. A cover may be provided for the locking mechanism.

30 The side frame 3 is connected to a link 67 by a pin 68. The opposite end of the link 67 is connected to a gear segment lever 69 by a pin 70. This gear segment lever 69 meshes with a gear segment 71 which, in turn, is fastened to the eccentric pin 11. Thus when the side frame 3 is rotated on the pin 11, this pin is caused to rotate, which, because the eccentric portion of the pin supports the pinch wheel 7, causes these rolls to be raised or lowered.

40 The operation of the tool is as follows:

45 A piece of box strapping 35 is placed around a package with its ends overlapping. With the lever 46 in the top position, and the side frame 3 tipped back, the tool is placed over the box strapping, so that the overlapping ends of the strapping lie between the block 4 and the pinch wheels 7. A sleeve 33 of the type shown in Figure 8 is placed in the opening 72 of the base 2 and over the overlapping ends of the box strapping. The side frame 3 is moved to a vertical position, which 50 causes the jaws 24 to be lowered to a position where their ends are adjacent the sides of the sleeve 33, thus holding the box strapping in a central position between the jaws. By moving the side frame 3 to a vertical position, the pinch 55 wheels 7 are caused to be lowered, thus causing these wheels and the pinch block 4 to tightly grip the strapping.

60 The next operation is the tensioning of the band. This is accomplished by an up and down movement of the lever 16, which causes the wheels 7 to rotate and pull the top end of the strapping past the lower end which is held in place by the block 4. The stationary pawl 21 holds the wheels 7 against rotation when the lever 65 16 is released.

65 Next the fastening is made by moving the lever 46 in a downward direction. As this lever 46 is being moved downwardly the crosshead 43 comes to a position where its top edge is below the pin 70 54. When this happens this pin 54 snaps behind the crosshead 43, thus preventing the lever 46 from being raised until the pin 54 is removed. Since the lever and crosshead must be raised to

separate the jaws 24, these elements being interconnected, the tool is locked to the work by the pin 54. Furthermore, this prevents movement of the side frame 3 to release the pinch wheels 7, so that the straps are locked in tension. By a 5 further downward movement of the lever 46 the shearing surfaces 27 of the dies 26 are caused to engage the sides of the box strapping 34 and shear the same along the edges 36 and complete the fastening.

10 At the extreme lower position of the lever 46, the surface 62 of this lever engages the pin 61 which, in turn, engages the adjustable screw 63. A movement of this pin 61 in the direction of the lever 52 causes this lever to be rotated until the 15 latch 56 latches on the surface 58. This causes the end of the pin 54 to be withdrawn from above the crosshead 43, and allows the lever 46 to be moved to its top position, thereby moving the jaws 24 to an open position. The side frame 3 20 is now rotated to a back position, which releases the pinch wheels 7 from engagement with the strapping and allows the tool to be removed.

25 Although a specific example of a tool is here disclosed in accordance with the patent statutes, it is to be understood that various changes may be made in the same without departing from the scope of the invention, as defined in the following claims.

I claim:

30 1. A tool including the combination of a base on the top of which overlapped ends of package strapping may be placed, mechanism for interfastening said ends, said mechanism being mounted to move toward and from said base, a toothed wheel mounted above said base to move toward and from the same so that it may engage or disengage the top one of said ends, means responsive to movement of said mechanism toward said base for effecting movement of said wheel 40 toward the same and to movement of said mechanism from said base for effecting movement of said wheel from said base, means for revolving said wheel to move the top one of said ends when said wheel is engaged therewith, and means for preventing movement of the bottom one of said ends when said top one is so moved.

45 2. A tool including the combination of a base on the top of which overlapped ends of package strapping may be placed, mechanism for interfastening said ends, said mechanism being mounted to move toward and from said base, a pin journaled above said base transversely respecting said ends, a toothed wheel carried by said pin, the portion of the latter carrying said 50 wheel being set off-center so that rotation of said pin moves said wheel toward and from said base whereby it may engage and disengage the top one of said ends, a gear element fixed to said pin, a second gear element meshing with the first named one, a lever fixed to said second element, a connecting-rod arranged between said lever and said mechanism, the latter being pivoted to swing about said pin whereby its movement effects rotation of the same through said 55 connecting-rod, lever and gear elements, means for revolving said wheel to move the top one of said ends when said wheel is engaged therewith and means for preventing movement of the bottom one of said ends when said top is moved by 70 said wheel.

CLARENCE O. CARLSON.
